UNITED STATES PATENT OFFICE.

CHARLES F. JAEHN, OF ST. LOUIS, MISSOURI.

DRIVING-GEAR.

SPECIFICATION forming part of Letters Patent No. 761,494, dated May 31, 1904.

Application filed September 26, 1903. Serial No. 174,800. (No model.)

To all whom it may concern:

Be it known that I, CHARLES F. JAEHN, a citizen of the United States, residing at St. Louis, State of Missouri, have invented certain new and useful Improvements in Driving-Gear, of which the following is a full, clear, and exact description, reference being had to the accompanying drawings, forming a part hereof.

10 My invention has relation to improvements in driving-gear for pulleys; and it consists in the novel construction of gear more fully set forth in the specification and pointed out in the claims.

15 In the drawings, Figure 1 is a combined section and elevation of one end of the pulley with shaft in cross-section. Fig. 2 is a middle vertical transverse section on line 2 2 of Fig. 1. Fig. 3 is a transverse vertical section 20 on the broken line 3 3 of Fig. 2. Fig. 4 is a transverse vertical section on line 4 4 of Fig. 2. Fig. 5 is an edge view of the collar carrying the coupling-lever with side view of the upper end of the lever. Fig. 6 is a view 25 at right angles to Fig. 5, and Fig. 7 is a cross-section in line 7 7 of Fig. 6.

The object of my invention is to interpose between a drive-shaft and its pulley gear mechanism by which it may be possible to impart 30 to the pulley a motion of rotation in a direction contrary to that of the shaft, so that the necessity of cross-belts shall be dispensed where it is desirable to impart from said pulley motion to a counter-shaft in such reverse 35 direction.

A further object is to provide means for disengaging the pulley from said shaft, converting the same for the time being into a loose pulley, and bringing the counter-shaft to a 40 standstill.

In detail the invention may be described as follows: Referring to the drawings, S represents a drive-shaft, and P a loose pulley mounted on the same. Secured to one end of the inner rim of the pulley and rotatable with it about the shaft is a cover-plate 1, provided on its inner face with an annular groove or way 2 for the support and free traverse of the bearing-blocks 3, which carry the adjacent ends

of the spindles 4 of the series of pinions 5, 50 the opposite ends of the spindles being mounted in the female member or rotatable disk 6 of the clutch mechanism by which the pulley is coupled to the shaft, (as presently to be seen.) Disposed about the shaft and confined 55 within the inner rim of the pulley and flush with the opposite end of said rim is a stationary plate or disk 7, constituting the male member of the clutch, said disk being provided with suitable openings for the free passage 60 therethrough of the arms of a fork 8, the free ends of the fork-arms being adapted to frictionally engage the walls of an annular groove 9, formed in the adjacent face of the member 6. The base of the fork 8 is carried by a coupling-lever 10, whose one end is hinged to a collar 11, through which the shaft loosely passes, the collar 11 being confined in position by the collars 12 12, clamped tightly to the shaft on each side of it. The free end of the lever 10 70 is provided with a spring-pawl 13, operating in conjunction with a curved rack 14 and being of a construction which is well known and not herein claimed. The disk 7 is permanently stationary, being held in position by 75 the arms of the fork 8, which find a permanent bearing therein. The periphery of the disk 7 is provided with a series of pockets 15 for the reception of a series of antifriction-rollers 16, over which the adjacent surface of 80 the inner rim of the pulley travels while coupled to the shaft, thereby materially reducing the friction between the parts.

Keyed to the shaft and adapted to mesh with the several pinions 5 is a gear-wheel 17, 85 the pinions likewise meshing with the toothed or geared section 18 of the inner surface of the inner rim of the pulley. The latter is retained on the shaft by the collar 12'.

The operation of the device is as follows: 90 With the position of the coupling-lever shown in Fig. 2 where the female member 6 of the clutch is free to rotate about the shaft, (the fork 8 being wholly disengaged from the groove 9, formed for the reception of the arms of said fork,) then assuming that the shaft S rotates in the direction shown by the arrow, Fig. 1, the gear-wheel 17 rotates the pinions

5, causing the latter to simply travel around over the toothed section 18 of the pulley, (held against rotation by the resistance offered by the tension of the drive-belt leading to the machinery to be driven,) the pulley remaining stationary under the circumstances. In thus rolling around on said toothed section 18 the pinions carry the member 6 about the shaft, and the bearing-blocks 3, in which are mounted 10 the adjacent ends of the spindles 4, loosely traverse the groove or way 2, provided for them for this purpose. The moment, however, that the lever 10 is swung to the dotted position, (shown in said Fig. 2,) whereby the 15 fork-arms 8 are forced into frictional engagement with the groove 9 of the female member 6, the latter is instantly locked against rotation, and the shaft while still rotating in the same direction now causes the pinions 5 to drive the pulley in the same direction with them (see arrows in Fig. 1)—that is to say, 20 in a direction contrary to the rotation of the shaft. The pulley is obliged to rotate in the direction here indicated, since the resistance offered by the fork 8 to the rotation of the disk 6 is greater than that to be overcome by the pulley in driving its belt and the machinery impelled thereby.

It is to be understood that I may depart from 30 the details of construction here shown without in anywise affecting the nature or spirit of my invention. Obviously the invention need not be limited to pulleys, but may be applied to any revoluble bodies.

35 Having described my invention, what I claim is—

1. In a driving-gear, a rotatable shaft, a pulley mounted loosely thereon, a gear-wheel fixed to the shaft within the pulley, an interior 40 toothed section formed on said pulley, a series of pinions meshing with the respective toothed surfaces, spindles for the pinions, a disk loosely mounted on the shaft and serving as a bearing for the adjacent ends of the spindles, the opposite ends of the spindles being supported by the pulley, and means for holding the disk stationary during the rotation of the shaft, substantially as set forth.

2. In a driving-gear, a rotatable shaft, a pulley mounted loosely thereon, a gear-wheel fixed to the shaft within the pulley, an interior toothed section formed on said pulley, a series of pinions meshing with the respective toothed surfaces, a disk loosely mounted on the shaft 55 and serving as a bearing for the adjacent ends of the spindles of said pinions, a suitable groove or way being formed in the pulley for the support of the opposite ends of the said spindles, and means for holding the disk stationary during the rotation of the shaft, substantially as set forth.

3. In a driving-gear, a rotatable shaft, a pulley mounted loosely thereon, a gear-wheel fixed to the shaft within the pulley, an interior 60 toothed section formed on said pulley, a series

of pinions meshing with the respective toothed surfaces, spindles for said pinions, a disk loosely mounted on the shaft and serving as a bearing for the adjacent ends of the spindles of the pinions, a groove or way being formed in the pulley for the opposite ends of the spindles, a second disk passed loosely over the shaft, a lever pivoted in proximity to the last disk, a fork carried by the lever and passing loosely through and permanently engaging the second 70 disk, the arms of the fork being adapted to be frictionally forced into engagement with the first-mentioned disk and hold the same stationary during the rotation of the shaft, substantially as set forth. 75

4. In a driving-gear a rotatable shaft, a pulley having an outer and an inner rim loosely mounted on the shaft, a cover-plate closing one end of the inner rim, a way or groove being formed on the inner face of said plate, 80 a disk confined within the inner rim and free to rotate about the shaft, a second disk mounted adjacent thereto within the inner rim, a series of antifriction-rollers mounted on the periphery of the second disk, a toothed section formed along the inner surface of the inner rim, a gear-wheel keyed to the shaft within said toothed section, a series of pinions respectively meshing with said gear-wheel, and the toothed section of the inner rim, bearing-blocks loosely confined within the way of the cover-plate, the spindles of the pinions having their opposite ends respectively supported in said bearing-blocks and in the first-named disk, and means for coupling the two 85 disks together and holding them stationary during the rotation of the shaft, substantially as set forth. 90

5. In a driving-gear, a suitable shaft, a pulley mounted loosely thereon, a disk mounted 95 loosely on the shaft within the pulley, a second disk loosely embracing the shaft and located adjacent to the first disk, a collar loosely embracing the shaft at a point beyond the second disk, a lever pivotally suspended from 100 said collar, a fork carried by the lever, the arms of said fork passing through suitable openings in the second disk, a groove being formed on the adjacent face of the first disk 105 for the reception and frictional engagement of the ends of the arms of said fork, and intermediate gearing between the pulley, the shaft and inner disk for imparting rotation to the pulley in a direction reverse to that of the shaft, while the inner disk is held against rotation by the frictional engagement of the fork, substantially as set forth. 110

6. In a driving-gear, a rotatable shaft, a pulley mounted loosely thereon, a gear-wheel fixed to the shaft within the pulley, an interior 115 toothed section formed on said pulley, a series of pinions meshing with the respective toothed surfaces, spindles for the pinions, a disk loosely mounted on the shaft and serving as a bearing for the adjacent ends of the spin- 120

dles of said pinions, a groove or annular way being formed with a pulley for the free traverse of the opposite ends of the spindles, the pinions being free to roll along the geared section of the pulley for a released position of the disk during the rotation of the shaft, substantially as set forth.

In testimony whereof I affix my signature in presence of two witnesses.

CHARLES F. JAEHN.
